P. Chase,

Steam-Boiler Furnace,

Patented Oct. 7, 1831.

Oct 7, 1831

6789X

Paul Schae.

2
M. A. Poston

The schedule referred to in these Letters Patent and making part of the same containing a description of the works of the said Paul Schae himself of his improvement in the mode of applying high Steam & Hydrogen Gas, to an improving combustion in the use of Anthracite Coal.

2) Description of an invention to apply high Steam and Hydrogen Gas to aid in producing combustion in the use of anthracite Coal.

This is done by two or more tubes or cylinders placed sufficiently near the grate bars in the furnace of steam boilers, which being heated by the same fire & supplied with water by a force pump, the water is instantly converted into hydrogen or inflammable gas, which is taken by the increased draft supplied by the large flue (hereafter described) and united with air, produces sufficient flame to ignite the fire of a steam boiler or steam generator.

The large flue is intended to be placed on the inner part of the grate bars for the purpose of creating sufficient draft to increase the consumption of Oxygen & quicker combustion in the use of a Anthracite Coal.

The water fans are to be constructed in the bottoms (the construction of the bottoms is only claimed) to produce action in the water placed in them, to unite in effect with the above described tube or tubes or gas generators to accelerate their operation, New York 26 March 1831.

2) Description of the large flue, mentioned in the aforesaid plan.

The flue is made in the front wall of the furnace two inches wide extending across the width. A little space is made in the wall under the grate bars, through which the air passes into the flue, an iron door is placed at the top of the flue it is built with, by which the flue is opened & shut as occasion may require.

2) The water fans. The water fans have one of iron plates two inches above the bottom and five inches apart, which are intended to create a positive action in the water when the heat or vapor is in motion.

2) Other part to give outline upon the effect of the water in producing

2784

combustion & expansion of heat in steam boiler, and in all cases where steam is used for other purposes. The Compound Blow Pipe, or air pump, is considered unsafe to coincide with the water in producing the same effect, unless the draft is not sufficient.

Description of the Compound Blow Pipe, or Force Pump, No.

mentioned in the annexed plan. The upper & lower ends of it are made of wood to be of a circular form, of the size or diameter of the cylinder of the steam engine and of the length of the piston rod, at the middle of the pump, that is to say, equidistant from the ends, it is fixed to the guide rods, as represented in the plan, C. is fastened to a cross head, being the upper part of the frame & is connected with the lever beam, from which the motion is obtained, a pipe I leads from one side to a point equidistant distant from each end as represented in the plan to point Z, and the covering or outside of the pump is made of leather supported by four wooden rings at equal distances from the ends and from each other as represented by the letter K.

The compound Blow Pipe or force Pump is to be placed in an iron frame as represented in the side view. C represents the rod connecting the pump with the lever beam, from which the motion up & down is obtained; the frame is fastened at the bottom, two iron rods one on each side of the pump, further at the bottom run thro' the middle partition, which is also of wood & the top or upper end of the pump & are fastened to the cross head so as to play freely, the upper half or section of the pump from which pipe I proceeds operating as a reservoir.

At the side of the lever beam A the bottom of the pump is typed up & the air carried from its lower section thro' the valve M. 1. in the middle partition into pipe I. & files at the same time the upper section of the pump or reservoir thro' the down stroke of the lever beam A, the valve M. 1 is closed, and the air in the upper section or reservoir is carried forward into pipe I, which contains the blast. The same down stroke for the lower section at valve M. 2 and is continued by any operation of the lever beam A carrying forward air to point Z, being the point of contact for air & water & is calculated to carry eight parts air to twenty one the hundred of water which unite at point Z, and are carried into water. — all.

The outlet of I. is three inches in diameter, made of wrought iron, or cast iron, and placed under the great board, with holes between the great

6-1045

from which the decomposes an explosive mixture of Hydrogen gas or high
However, the gas is taken up by the air within the body of ignition is followed and
and produces combustion and expansion of heat which is carried thru the flue
of the furnace tubes. The diameter of all the holes in the sector A. The which
the gas is to escape must, taken together, be equal to the diameter of the retort itself.
The drawing fully explains the principles of the instrument. The ap-
plication of it must vary according to the position of the Engine & Boiler to
which it may be applied. The air pump is considered useful in cases where
there are a deficiency in the draft.

The force pump for water is known to all engineers and a description of
it is deemed unnecessary. It may be placed as represented in the draw-
ing and D, being the connecting pump.
